MOVING AND DISTRIBUTING SENSITIVE MATERIAL

Warren S. Reynolds, Westport, Conn., assignor to Remington Arms Company, Inc., Bridgeport, Conn., a corporation of Delaware

Application October 31, 1952, Serial No. 317,866

8 Claims. (Cl. 86—32)

This invention relates to the handling and distribution in a dry state of combustible or explosive materials which are inherently sensitive to friction and percussion and tend to be sensitive to static electricity.

More specifically, the invention relates to apparatus for the handling of bulk quantities of dry ammunition priming compositions, distribution of the bulk material into individual charges, and the transfer of such individual and measured charges into primer cups adapted for insertion into cartridge cases.

Ammunition priming compositions comprise essentially an admixture of an oxidizer, a fuel and a percussion-sensitive ingredient with or without the addition of a friction material such as ground glass. They are necessarily and inherently sensitive to friction and percussion and tend to be sensitive to an electric spark. While it is sometimes feasible to prepare and distribute such materials in a moistened and pasty condition, it is frequently more desirable to prepare and load them dry. While loaded containers of such dry mixtures can be handled with comparative safety, the distribution of a bulk quantity of dry mixture into individual charges and the transfer of such charges into primer cups is a hazardous operation, since friction of the mixture upon itself or against any hard objects or the passage of an electric spark in any part of the mixture almost inevitably effects a local ignition which results in the rapid combustion of the entire mass.

The present invention contemplates apparatus for receiving a container of bulk mixture and substantially automatically transferring the container to a delivery point, dumping the contents of the container upon a charger plate, and returning the container to its initial position. Thereafter, the material delivered upon the surface of the charger plate is distributed into individual charges by brushing it into measuring apertures or holes in the charger plate, from which holes it is delivered into primer cups positioned beneath the holes. The distribution of the mixture and its transfer into the primer cup, as well as the movement of the container carrying the mixture in bulk, are substantially automatically performed under remote control, eliminating the necessity of an operator in the immediate vicinity of any operation in which the mixture is being moved or shifted either upon itself or with respect to any external object.

In the drawings:

Figs. 1 and 1A together show a longitudinal elevation of the machine, some parts being sectioned or broken away for greater clarity.

Fig. 2 is a plan view of that part of the machine shown in Fig. 1.

Fig. 3 is a fragmentary transverse sectional elevation substantially on the line 3—3 of Fig. 2, some parts being omitted, for greater clarity.

Fig. 4 is an elevation at the right end of Fig. 2.

Fig. 5 is a transverse sectional detail of the charger plate and associated parts.

2

Fig. 6 is a simplified wiring diagram.

The machine of the invention is especially adapted for use adjacent the outside wall of a building, in which wall there is an opening constituting a receptacle for a limited number of containers or pouches of dry priming composition as delivered from the mixing operation. Such pouches are transferred one-at-a-time to a carrier identified generally by numeral 10 which is carried by and projects laterally from a conveyor comprising a pair of chains 11a and 11b. The conveyor chains traverse idler sprockets 12 (Fig. 1A) and driven sprockets 13 (Figs. 1 and 2), which driven sprockets are secured to a shaft 14 having fixed thereon a sprocket 15 which is driven from a suitable source of power such as a motor C. As clearly shown in Figs. 2 and 3, the carrier proper consists of an open frame of longitudinally and transversely extending rods, one end of each transversely extending rod being turned inwardly over the compartment defined by the rods as shown at 101 (Fig. 1) while the outer and free ends of certain of the longitudinally extending rods are turned outwardly, as shown at 102 (Fig. 3), to facilitate the placement in the carrier of a container or "pouch" of priming mixture, the pouch 17 and contents thereof being indicated in section in Fig. 1. The turned portions 101 of the transversely extending rods hold the pouch 17 in the carrier when it is inverted, as hereinafter described.

A loaded pouch having been placed in the carrier 10 at position A, Fig. 1, the motor C is activated to transport the pouch to a position above the charger plate. This is accomplished by manipulation of the manual switch SC (Fig. 6) which may be located at any desired point. As illustrated in the circuit diagram, Fig. 6, closing of the switch SC activates the solenoid So₁ to close the switch Sw₁ which is in the circuit to the conveyor motor C. Switch Sw₁ comprises an auxiliary contact by which the starting switch SC is shortcircuited when switch Sw₁ is closed. The carrier with the pouch therein is transported by the conveyor 11a—11b to position B, Fig. 1A, over a charger plate 20. At this point an arm 21 (Figs. 1, 1A and 4), associated with the carrier mounting, engages the nose of a stationary cam 22, and in its movement to position C, Fig. 1A, the carrier and pouch are rotated through 90° (Fig. 1A shows the outline of the pouch only, the carrier 10 being omitted). Upon further movement of the carrier, an arm 23 on the carrier mounting engages a second cam nose 24 and, in its additional movement, to position D, the carrier is completely inverted, dumping its entire content upon the charger plate 20. At about this point in the movement of the carrier and conveyor, a cam 25 formed on a link of conveyor chain 11a (Figs. 1 and 1A) engages an operator 26 of a reversing switch SR (Figs. 1 and 6) which, by means of the circuits illustrated in Fig. 6, serves to reverse the motor C and restore the conveyor and carrier to the carrier loading position illustrated in Fig. 1. During return movement of the carrier, the aforementioned arms 21 and 23 associated therewith successively engage fixed cams 28 and 29, completing a 360° rotation of the carrier, so that it is returned to position A upright and ready for re-loading. As the carrier approaches position A, a cam 30 on conveyor chain 11b engages and displaces an operator 31 for the limit switch SL which, as shown in Fig. 6, disables the solenoid So₂ which has held the line switch Sw₂ closed, and thus stops the conveyor motor C.

The charger plate 20, upon which the bulk mixture is delivered, as heretofore described, is one element of an assembly, illustrated in detail in Fig. 5, by which the mixture is distributed into primer cups P. Plate 20 comprises a plurality of measuring apertures 201 into which the mixture is brushed, as will be presently described.

Said plate 20 overlies a bottom plate 35 which in turn overlies a cup plate 36 provided with recesses for holding the cups P. Bottom plate 35 comprises apertures or passages 351 through which the mixture passes from the measuring apertures 201 to the cups P. It will be understood that each aperture 201 is normally out of line with the corresponding aperture 351 and that in a typical assembly the charger plate 20 is moved to align said apertures, as shown in Fig. 5, and effect delivery of the measured charge to the primer cup. Pneumatic or other means (not shown) may be provided for effecting the movement of charger plate 20, and a vibrator (not shown) may be applied to said plate to insure complete delivery.

The means for automatically distributing the bulk mixture upon the charger plate into the measuring apertures 201 therein may comprise a wiper 37 (Figs. 1A and 4) of rubber, neoprene or other like material. The wiper is so controlled that it traverses the length of the apertured portion of the charger plate in contact therewith, pushing the bulk priming mixture ahead of it. Having completed one traverse of the apertured portion of the plate, the wiper is lifted and passes over the pile of mixture, then lowered to again engage the plate, rocking to a position somewhat inclined to a perpendicular to the plate, then traverses the plate in the opposite direction, where it is again lifted and passes over the remaining pile of mixture. The positions of the wiper, behind the heap of mixture and ready to begin each traversing movement, are shown in Fig. 1A. This operation is repeated for a predetermined number of cycles; after which the wiper is stopped to enable the removal of the loaded cup plate and its replacement by an empty cup plate. The devices for this purpose may be constructed as follows:

The wiper is carried upon a stem 38 received in a socket 39 projecting from a boss 40 loosely mounted on a tubular shaft 41 extending lengthwise of the machine and supported for rotational and translational movement in bearings 42 in fixed brackets 43. A set screw 44 in socket 39 engages a peripheral groove in stem 38, retaining said stem against longitudinal displacement while permitting its rocking movement to vary the inclination of the wiper to the charger plate, as above described. An arm 45 secured to shaft 41 is provided with a stud 46 which underlies socket 39 to effect the lifting of the wiper upon rotation of shaft 41 in the manner to be presently described. It will be understood that the wiper participates in the translational as well as the rotational movement of the shaft 41.

The means for moving shaft 41 in the direction of its length, to effect translation of the wiper, comprises a motor W (Figs. 1 and 6) which drives a vertically disposed stub shaft 47 having secured thereto a crank 48 joined at 49 to a connecting rod 50 which is coupled at 52 to shaft 41 by a connection which moves the shaft longitudinally while permitting its separate rotation. The wiper 37 thus moves from one end to the other of the charger plate 20 during each half revolution of the crank 48, and returns to its initial position during the next half revolution of the crank 48.

The means for rotating the shaft 41, to lift the wiper near the end of each translational movement, comprises a cam plate 53 secured to a gear 54 driven by a pinion 55 secured to stub shaft 47. The cam plate carries a plurality of cams 56 adapted for sequential engagement with cam follower 57 carried by an arm 58 extending from a boss 59 which has a spline connection with shaft 41. The gearing 54-55 is so arranged that shaft 41 is thus rotated a few degrees as the wiper approaches each end of its charger plate traversing movement, enabling the wiper to pass over the pile of priming mixture pushed in front of it and to again shove the mixture in front of it on its return movement. The drawings illustrate an arrangement in which the wiper performs six passes over the charger plate, but it will be apparent that by a re-

arrangement of the gear connection 54-55 and the cams 56 any desired number of passes can be secured, it being understood that gear 54 and cam plate 53 complete one revolution before being stopped in the manner to be presently described.

The means for stopping the movement of the wiper after it has traversed the charger plate a desired number of times comprises devices for breaking the circuit which supplies current to wiper motor W. Movement of the wiper is initiated by momentarily closing the manual switch SW; the circuit, as illustrated in Fig. 6, being such that switch SW is short circuited by the closing of the switch FW as soon as cam plate 53 starts its movement. Switch FW is supported adjacent cam plate 53 and is controlled by an operator 60 adapted for engagement with a cam 61 mounted on cam plate 53. The circuit diagram, Fig. 6, will show that when cam plate 53 has completed a full revolution switch FW will be opened by the engagement of operator 60 with cam 61 and, the manual switch SW being open, the line switch SW₂ will be opened by the de-energization of its closing solenoid S₀₂. The filling of a charger plate is thus automatically completed, and any disturbance of the priming mixture in or upon the charger plate is stopped without any hand manipulation. The charges which have been distributed in the holes 201 in the charger plate are dumped into the cups in the cup plate 36, which plate is then removed and replaced. The wiper is again started by closing the manual switch SW and the operation is repeated until the charge of bulk material upon the charger plate is nearing exhaustion; thereupon, the conveyor is again activated to deliver another pouch of mixture to the charger plate, as heretofore described.

Means are provided for preventing the activation of the conveyor motor C while the wiper is in operation and for preventing the activation of the wiper motor W while the conveyor is in operation. This means comprises the electrical connections and switches illustrated in Fig. 6. The circuit through the conveyor starting motor solenoid S₀₁ comprises a switch SI actuated by an operator 62 controlled by a cam 63 on the cam plate 53, the arrangement being such that switch SI is closed only when the cam plate 53 is in its home position and at rest. Thus, the motor C cannot be activated except when the wiper and associated parts are stationary. To prevent activation of the wiper motor during movement of the conveyor, starting circuit for the wiper motor W comprises the aforementioned switch SL which not only interrupts the circuit through the conveyor motor but completes the starting circuit for the wiper motor; thus, the wiper can be activated only when the conveyor is at rest in carrier loading position.

The complete assembly thus provides for the automatic and remote control of all operations incident to delivering bulk priming mixture to a charger plate, distributing it in the charge measuring holes in said plate, and dumping the measured charges into primer cups or other suitable receptacles in which the static and friction sensitive material is at rest and relatively innocuous.

What is claimed is:

1. Apparatus for distributing a pulverulent explosive material into apertures in a plate comprising a supporting frame; means for holding said plate in said frame; means for delivering said material to the upper surface of said plate; a wiper comprising a single plate-engaging blade adapted to traverse the surface of said plate in reverse directions; means associated with said frame for supporting said wiper adjacent the surface of said plate; wiper moving means mounted in said frame; and means activated by said wiper moving means for performing and completing a sequence of operations comprising moving said wiper across said plate in one direction, bodily lifting said wiper to clear said plate and the material thereon near the end of said traversing movement, lowering said wiper to re-engage the surface of said plate, moving said wiper across said plate in the reverse direc-

tion, bodily lifting said wiper to clear said plate and the material thereon near the end of such reversing movement, re-engaging said wiper with said plate, repeating the cycle of traverse, lifting and lowering movements of said wiper a predetermined number of times, and then stopping the movement of said wiper.

2. Apparatus according to claim 1, comprising a shaft supported in said frame and extending in the direction of the plate traversing movement of said wiper and an arm extending from said shaft and supporting said wiper.

3. Apparatus according to claim 2, comprising a prime mover and connections therefrom for translating said shaft in the direction of its length.

4. Apparatus according to claim 3, comprising means for rotating said shaft to lift said wiper to clear said plate and the material thereon near the end of the movement of said wiper in either direction.

5. Apparatus according to claim 4, in which said shaft rotating means comprises a cam plate moved by said prime mover in synchronism with the translational movement of said shaft and said wiper, cams on said cam plate, and a cam follower mounted on said shaft and extending into the path of movement of said cams.

6. Apparatus according to claim 5, comprising a control cam on said cam plate and means activated by said control cam for disabling said wiper moving means.

7. Apparatus according to claim 5, comprising a second control cam on said cam plate and means activated by said second control cam for controlling said material delivery means.

8. Apparatus for moving and distributing a pulverulent explosive material comprising in combination a supporting frame; an endless conveyor chain mounted on said frame; a carrier mounted on said conveyor chain and adapted to receive a container of said material; reversible motor driving means for said chain by which said carrier may be caused to perform a reciprocating movement from a material receiving position to a material delivery

position; manually actuatable control means for initiating operation of said driving means to transport said carrier away from material receiving position; cam means mounted on said frame and engageable with elements of said carrier as the carrier is reciprocated by the conveyor chain to invert the carrier to empty said container and to restore said carrier to upright position; limit switch means on said frame engaged by elements movable with said conveyor chain to reverse said conveyor after the carrier has reached its material delivering position and to stop said conveyor after the carrier has returned to material receiving position; a plate supported in said frame at said material delivery position and formed to define in its surface a plurality of charge forming apertures; a wiper adapted to distribute said material into said apertures and to wipe off the excess of said material flush with the face of said plate; means on said frame to support said wiper in operative relation to the surface of said plate and to cause it to perform a cycle of plate traversing movement; motor driving means for said wiper; and switch means for said wiper driving motor interlocked with the switch means for said conveyor motor to prevent movement of one driving means while the other is operating.
